David Walker

United States Patent Office.

DAVID WALKER, OF NEWARK, NEW JERSEY.

Letters Patent No. 77,783, dated May 12, 1868.

IMPROVEMENT IN BLOTTERS.

The Schedule referred to in these Letters Patent and making part of the same.

TO ALL WHOM IT MAY CONCERN:

Be it known that I, DAVID WALKER, of the city of Newark, in the county of Essex, and State of New Jersey, have made an improvement upon my already-patented Blotter; and I do hereby declare the following to be a full and exact description of the same, reference being had herein to the drawings that accompany this specification, making part of the same.

My improvement consists in the addition of a detached strip of metal, or other substance sufficiently hard, constructed and adapted to use as a ruler and as a paper-cutter, held to the edge by the same springs as confine the blotting-paper to the holder.

In the drawings—

Figure 1 is the patented blotter with the additional edging.

Figure 2 is an end view of the same.

Figure 3, the strip.

A strip of thin metal, or of any other substance sufficiently hard for the purpose, fig. 3, *a*, is shaped to fit close to the lengthwise edge of the blotter-holder, and is placed between the spring *b* and the blotting-paper, both paper and strip being thereby confined to the holder.

The lower edge of *a* projects sufficiently to be a convenient ruler, and also is a cutter or stripper for the paper, when, by a slight turn of the hand, the edge is pressed down on the paper.

What I claim as an improvement, and desire to secure by Letters Patent, is—

The thin strip of metal or hard substance *a*, constructed, adapted, and attached to the blotter, in the manner and for the purpose specified.

DAVID WALKER.

Witnesses:

W. M. GOODING,

SIDNEY U. EDWARDS.
